MAP HOLDER

Michel Pages, Dorchester Apts, 226 W. Rittenhouse
Square, Philadelphia, Pa. 19103

Filed Jan. 26, 1972, Ser. No. 221,117

Term of patent 14 years

Int. Cl. D19—99

U.S. Cl. D19—89

FIG. 1.

FIG. 2.

FIG. 3.

FIG. 1 is a perspective view of a map holder, showing my new design;

FIG. 2 is an end elevational view thereof, with intermediate portion broken away for convenience of illustration; and

FIG. 3 is an end elevational view of an alternative embodiment of the design of FIG. 1, with intermediate portion broken away for convenience of illustration.

I claim:

The ornamental design for a map holder, as shown and described.
